CLARENCE H. NICHOLS, OF NEW YORK, N. Y.

BOILER-OPERATING METHOD AND MEANS.

1,234,201.

Specification of Letters Patent. Patented July 24, 1917.

Application filed January 26, 1915. Serial No. 4,423.

To all whom it may concern:

Be it known that I, CLARENCE H. NICHOLS, a citizen of the United States, and a resident of the city and State of New York, have invented certain new and useful Improvements in Boiler-Operating Methods and Means, of which the following is a description.

My invention relates to steam boilers, and is directed to operating means and methods which greatly simplify the operation of boilers, reduce their operating cost, and dispense with a large amount of apparatus which is expensive to install, operate and maintain.

More particularly, my invention is directed to the operation of steam boilers in a battery of several boilers, arranged to supply prime movers, or steam consuming devices of any nature, and is particularly useful in instances in which the exhaust steam from the prime movers or other steam consuming devices is condensed and the condensate used as a feed water supply to the boilers.

Heretofore, in such an arrangement, when pure water was unobtainable, the practice has been to supply each of the boilers of a battery with water obtained by condensing the exhaust steam from the prime mover, and to make up any loss in water by an addition to the condensate of pure water obtained by distilling salt, or other impure water, taken from the main source of water supply. When so operated, a distilling plant consisting of a distilling boiler, a condenser and a pump was installed, the steam generated in the distilling boiler passing at approximately atmospheric pressure to the coils of the condenser, which coils were cooled by air or by water derived from some convenient source, the steam being thus condensed and the water of condensation pumped into the boiler feed water line. By the use of my invention, I am not only able to dispense with much of this auxiliary apparatus, but also to save substantially all of the heat loss incident thereto, thus greatly reducing the cost of operation of the plant.

Referring to the drawing accompanying this specification, I have shown at 1 a pipe line which is connected with the source of salt or impure water supply. The water passes from said pipe either through a heater 2, which may be heated by means

of the exhaust steam, or it may be by-passed around said heater by means of a pipe 3. The water then passes through a feed pump 4, and thence by means of pipe 5 to an economizer 6, which is usually heated by means of the waste gases of combustion, or, if desired, it may be by-passed about the economizer by a by-pass pipe 7. The water then passes by pipe 8, assuming valve 9 to be open and valve 10 to be closed, to boiler 11. Boiler 11 may be of any suitable construction but, inasmuch as it is used to evaporate salt or impure water, it is preferably of a construction from which the scale, sediment or other impurities may be easily removed. The water is evaporated in boiler 11 and steam of approximately the same pressure as that generated in the other boilers is generated therein, this steam passing by means of pipe 12 to the common steam-header 13.

At 14, 15 and 16, I have shown three other boilers of the battery, each connected to the steam-header 13 and feed-water line 17. The section of the feed water line 17, however, which supplies boilers 14, 15 and 16, is cut off from the remainder of the line by the closure of valve 10, thus supplying pure water derived from the condensation of the exhaust steam of the prime mover to boilers 14, 15 and 16, as will be explained. At 18-18, I have shown two prime movers, it being understood, however, that any desired number of prime-movers may be used. The steam passes from the common steam-header 13 to the prime movers by means of pipes 19-19, is utilized therein, and then passes through condensers 20-20, where the exhaust steam is condensed, and from which it is removed by means of pumps 21-21; 95 the condensate then passes by means of pipe 22 either to the heater 23, which may be conveniently heated by the exhaust steam, or by-passed about said heater by means of by-pass pipe 24, thus being led to feed pump 100 25 by means of which the water is pumped either to an economizer 26 and thence to the feed water line 17, or by means of a by-pass pipe 27, directly to the feed water line. A check valve 29 is located between each boiler 105 and the feed water line 17 to prevent a flow of water or steam from any of the boilers into the feed water line, such as would occur in the event of unequal pressures in the several boilers if these valves were omitted. 110

It will thus be seen that boilers 14, 15 and 16 are operating on pure water derived from condensation of the exhaust steam of the prime movers, and boiler 11 is operating upon impure water derived from the source of impure water supply. Steam of substantially the same pressure, however, is being generated in all of said boilers and delivered to a common steam-header 13 for use in the prime movers. I am thus enabled to 10 make up for any losses in pure water directly from boiler 11, without passing through the condenser in the manner now practised. It will be evident that I thus 15 save the amount of heat necessary to evaporate the make-up water, as well as saving the expense of maintenance, cost and cost of operation of the condenser, etc. While I have shown all of the boilers of the battery delivering steam to a common header, 20 it is to be understood that any one or any group of the boilers may be separately connected to a steam consuming device or devices.

Should the amount of water which boiler 25 11 is capable of evaporating prove insufficient to compensate for the feed-water losses, boiler 14 may be used in addition to boiler 11 for evaporating impure water, by 30 simply opening valve 10 and closing valve 28. Or, by slightly opening valve 28, I can allow a certain amount of pure water to pass therethrough and mingle with the impure water supplied to boiler 14, should 35 the combined capacities of boilers 11 and 14 be greater than that required.

Also, should the capacity of boiler 11 be greater than that necessary to supply the make-up water for the remainder of the 40 battery, I may decrease the amount of impure water supplied thereto by slightly opening valve 10, thus allowing some pure water to pass therethrough to boiler 11.

In this manner I may use any desired 45 number of the boilers of the battery to evaporate impure water, while the remaining boilers of the battery are operating on the pure water of condensation.

From the foregoing description it will be 50 seen that my invention has great utility in many instances in which it is desired to evaporate impure water, irrespective of the particular use to which the steam produced thereby is put. Thus, if instead of using 55 the condensate of the exhaust steam of a prime mover to supply feed water for boilers operating upon relatively pure water, it is desired to supply pure water to any water utilizing device as, for instance, in connection 60 with domestic uses, the manufacture of ice, etc., the prime mover may be omitted and any other suitable steam consuming or condensing device substituted therefor, or, if desired, a portion of the condensate may be 65 used for domestic uses, ice making, or other

purposes, and the remainder used to supply feed water to the boilers.

I, therefore, do not desire to limit my invention to a system in which all of the exhaust steam is condensed to be used as feed 70 water for the boilers or, in fact, to any specific use of the steam generated in the boilers of the battery, or to the use of all of such steam in any particular manner, since it is evident that a portion of it may be used in 75 one manner and another portion in another. Nor do I intend to limit myself to any particular steam or water consuming device, but intend to include all devices in which steam is consumed or condensed. I also do 80 not intend to limit myself to the precise nature, arrangement of the steam-consuming devices, or the piping, as these are matters of detail, and it will be evident that many modifications of my invention may be made 85 without departing from the spirit and scope of my invention.

What I claim is:

1. The method of operating a battery of steam boilers which consists in evaporating 90 the water of condensation secured by condensing the exhaust of a steam consuming device in part of the battery, and making up the loss of water for such boilers by evaporating impure water in the other part of the 95 battery, and supplying the steam so generated to the steam consuming device.

2. The method of operating a battery of steam boilers, which consists in evaporating the water of condensation secured by condensing the exhaust of a steam consuming device in some of the boilers of the battery to generate steam of a given pressure, supplying impure water to another boiler of the battery, generating steam therein at the 105 same pressure, and supplying the steam generated by all of the boilers to said common steam consuming device.

3. The method of operating a battery of steam boilers, which consists in evaporating 110 the condensate obtained by condensing the exhaust from a steam consuming device in some of the boilers of the battery, supplying such condensate, together with impure water, to another boiler of the battery, evaporating said condensate and impure water in said boiler and supplying the steam generated in all of the boilers to a common steam consuming device from the exhaust of which 115 said condensate is obtained.

4. The method of operating a battery of steam boilers, which consists in feeding relatively impure water to one boiler of the battery to generate steam, supplying relatively pure water to other boilers of the battery to generate steam therein, supplying steam generated from both pure and impure water to steam consuming devices, condensing the steam after it has passed through the steam consuming devices and supplying the con- 120 125 130

densate to the boilers using relatively pure water.

5. The method of operating a battery of steam boilers, which consists in evaporating the condensate obtained by condensing the exhaust steam from steam consuming devices in some of the boilers of the battery, evaporating relatively impure water in another boiler of the battery and supplying steam generated from the pure and impure water to said steam consuming devices.

6. Means for operating a battery of boilers, comprising a feed-water line having pure and impure water connections; means for feeding pure or impure water to any desired number of boilers of the battery; a steam consuming device; a common steam connection from all of said boilers to the steam consuming device; means for condensing the exhaust steam of said steam consuming device; and means for delivering the

condensate to the pure water connection of the feed water line.

7. Means for operating a battery of boilers, comprising a steam consuming device; 25 means for condensing the exhaust steam of the steam consuming device and for supplying such condensate to any desired number of boilers of the battery; a source of relatively impure water supply; means for supplying such impure water to one of the boilers of the battery and a common steam connection from all of said boilers to the steam consuming device.

In testimony whereof I have signed this 35 specification in the presence of two subscribing witnesses.

CLARENCE H. NICHOLS.
